DRIVING MECHANISM FOR VALVE CUTOFF INDICATORS

Fay D. Welden, Tuckahoe, N. Y., assignor to Valve Pilot Corporation, New York, N. Y., a corporation of New York

Application December 5, 1941, Serial No. 421,761

8 Claims. (Cl. 105—48)

This invention relates to means for operating the valve cut-off indicator of a steam locomotive valve pilot. In Caracristi Patents Nos. 1,627,076 and 1,704,381 instruments are described by which all of the factors governing cut-off which produce the maximum result at different speeds are converted into a single expression in terms of surface speed and combined with speed indicating mechanism. A pair of needles or pointers move over a common instrument dial mounted in the cab, one of these needles giving the converted reading based on the various factors governing cut-off, the other needle indicating speed. By keeping the two needles in registry, the engineer is assured that he is using the proper cut-off for maximum output for each speed. The cut-off needle is actuated through connections with the reverse mechanism, which is used to vary the cut-off. A rod connected to an arm on the tumbling shaft oscillates a cam in response to changes in cut-off, and a cam-follower, pressed against the cam by means of springs, is connected to a cable which actuates the needle in the cab. The conversion of the cut-off factors into a single expression is effected by means of the cam which is designed according to principles disclosed in Caracristi Patent No. 1,627,075. The whole apparatus, equipped with both indicating and recording instruments, is known as a valve pilot.

In practice it has been necessary to mount the cam box close to the tumbling shaft and, consequently, it has been necessary to employ a relatively long cable and cable conduit extending along the boiler from the cam box to the instrument within the cab. There are certain objections to this arrangement: (1) The springs urging the follower against the cam must exert a maximum pull of 55 pounds in order to insure the proper actuation of the cut-off needle, and this has necessitated the use of a large and expensive cam box. (2) The repeated expansion and contraction of the boiler, alternating between periods of use and rest, introduce errors in the hook-up which necessitate frequent adjustments of cam and cable settings. And (3) the cam being separated from the indicating instrument by the length of the cable, errors arising through maladjustment of connections between the two, including the one enumerated above, are inevitable.

It is the object of the present invention to overcome these objections, an object that I have attained by moving the cam to the instrument itself, where it acts directly on the cut-off indicating mechanism, and oscillating the cam in re-

sponse to changes in cut-off by means of a hydraulic pressure transmitting system. Only very light springs are thus required to hold the follower against the cam, because, with the elimination of the long cable and the friction developed within its curving conduit, the work done by the cam is greatly lessened and the need for a separate cam box is eliminated. Expansion and contraction of the boiler do not adversely affect the hydraulic pressure transmitting system and introduce errors requiring adjustments, and as the cam acts directly on the instrument it is designed to control, there are no intermediate connections to suffer maladjustment.

In the accompanying drawings I have illustrated a preferred embodiment of my invention. In these drawings, Figure 1 is a side elevation of a conventional locomotive showing the mechanism of the present invention installed, and Figure 2 is a diagrammatic layout of the mechanism.

In these drawings, 1 indicates the cut-off valve. This valve is reciprocated through the usual operating gear comprising a pitman 2 driven from the middle driver, a link 3 provided with an arcuate slot 4, and a connecting rod 5, the latter being connected to the link 3 by means of a pin 6 passing through the slot 4. The link 3 is oscillated about a point lying midway between the ends of the slot 4 and hence the point of cut-off is determined by the position of the pin 6 in the slot 4. This position may be varied by the engineer through the operation of the reverse gear. In the drawings I have indicated a power-reverse gear 7 controlled from the cab by means of a rod 8. Extending from the power-reverse mechanism is a reach rod 9 pivotally connected to one arm of a bell-crank lever 10 fixed upon the tumbling shaft 11. The other arm of the bell-crank lever is connected by means of a link 12 to the cut-off valve connecting rod 5. Thus as the reverse gear oscillates the bell-crank lever 10 the position of the pin 6 is moved up or down along the slot 4. The foregoing is standard construction and, of itself, forms no part of the present invention.

Mounted within the cab of the locomotive is an instrument 13 provided with a dial marked in miles per hour and having two coaxially mounted needles or pointers. One of these indicates speed and is actuated by any suitable means, preferably through connections with a friction wheel 14, which engages the tread of one of the drivers. The speed indicator driving mechanism illustrated is that described and claimed in my co-pending application, Serial No. 421,762, filed December 5,

1941, but any other driving mechanism such, for example, as the one illustrated in the Caracristi Patent No. 1,704,381, might be employed. The second needle indicates cut-off and is responsive to changes in cut-off effected by the mechanism previously described. I shall now describe the mechanism for actuating the cut-off needle.

A cam 15, so designed as to convert cut-off factors into a single expression, is mounted within the instrument housing. A cam follower 16, which rises and falls with the oscillation of the cam, is mounted on a rack 17 which meshes with a pinion 18 fixed with relation to the cut-off needle 19, and thus the needle is swung as the cam is oscillated. A recording mechanism 20 may also be operated through the cam, as illustrated. The cam 15 is oscillated in response to oscillations of the tumbling shaft by means of the following mechanism: Fixed to the tumbling shaft 11 is an arm 21 connected by means of a horizontal rod 22 to a vertical arm 23 pivoted on the frame of the locomotive. The arm 23 thus oscillates with the tumbling shaft. Between the arm 23 and the cam 15 I have interposed a hydraulic pressure transmitting system which I shall now describe.

This system comprises a primary or driving cylinder 24 and a secondary or operating cylinder 25 interconnected by means of tubing 26 and the whole system filled with an oil or other suitable liquid. Each cylinder is provided with a piston and piston rod—27 and 28 respectively in the driving cylinder, and 29 and 30 in the operating cylinder—each piston rod extending on both sides of its piston and through stuffing boxes in the cylinder heads. By this construction the volume of liquid displaced is equalized and the pistons are supported throughout the length of their strokes. The non-working end of each piston rod is provided with a protective housing 31. The piston rod 28 is connected to a cross-head 32 sliding in ways 33. A connecting rod 34 extends from the cross-head 32 to the lower part of the vertical arm 23 so that oscillation of the tumbling shaft causes reciprocation of the cross-head and of the piston 27. The piston rod 30 of the operating cylinder 25 is provided at its upper end with a rack 35 which meshes with a pinion 36 fixed to the cam 15.

As the engineer varies the cut-off by operation of the power-reverse gear, the tumbling shaft is oscillated and with it the arm 21, which, acting through rod 22, arm 23, connecting rod 34, cross-head 32, piston rod 28 and piston 27 causes movement of the liquid in the two cylinders 24 and 25 and the connecting tubing 26 of the hydraulic pressure system, which, in turn, acting through piston 29, piston rod 30, rack 35 and pinion 36, oscillates the cam 15, which in its turn actuates the cut-off needle 19. Thus as the speed of the locomotive varies, the engineer can correspondingly vary his point of cut-off to maintain the speed indicating and cut-off indicating needles in registry. Each branch of the tubing 26 is provided with a pressure equalizer 37 by means of which the setting of the cam 15 may be adjusted from time to time.

In order to adjust the throw of the connecting rod 34 to obtain correct piston displacement for any tumbling shaft movement, I have provided the upper end of the arm 23 with a slot 38 for receiving the end of the rod 22. The position of the end of this rod relative to the rod 34 may be varied by means of two setscrews 39 bearing 70

on opposite sides of a bushing 40 in which a pin 41 on the end of the rod 22 is journaled.

The objects of my invention are attained by means of the apparatus illustrated and described.

5 The cam has been moved to the instrument itself where it acts directly on the indicating mechanism without the interposition of a long cable, thus increasing accuracy. The heavy cam box with its massive springs have been eliminated and the power required reduced. Expansion and contraction of the boiler do not introduce errors of adjustment calling for continuous correction. In all of these respects the present apparatus is an improvement over its predecessors.

15 It is common practice to combine recording with indicating mechanisms, and the term "cut-off indicator" used herein is intended to embrace either, or both.

I claim:

20 1. In a steam locomotive having means for varying cut-off, a cut-off indicator in the cab of the locomotive, means at the indicator for converting into a single expression factors governing cut-off which produce the maximum results at 25 different speeds, means for actuating the indicator by the converting means, and means for actuating the converting means in response to variations in cut-off.

2. In a steam locomotive having means for 30 varying cut-off, a cut-off indicator in the cab of the locomotive, a cam at the indicator for converting into a single expression factors governing cut-off which produce the maximum results at different speeds, means for actuating the indicator in direct response to oscillations of the cam, and means for oscillating the cam in response to variations in cut-off.

3. In a steam locomotive having means for 35 varying cut-off, a cut-off indicator in the cab of the locomotive, means at the indicator for converting into a single expression factors governing cut-off which produce the maximum results at different speeds, means for actuating the indicator by the converting means, and a hydraulic 40 pressure transmitting system for actuating the converting means in response to variations in cut-off.

4. In a steam locomotive having a reverse gear, 45 which varies cut-off, a cut-off indicator in the cab of the locomotive, a cam at the indicator for converting into a single expression factors governing cut-off which produce the maximum results at different speeds, means for actuating the indicator in response to oscillations of the cam, and a hydraulic 50 pressure transmitting system connected to both the reverse gear and the cam for oscillating the cam in response to variations in cut-off.

5. In a steam locomotive having a reverse gear, 55 which varies cut-off and includes a tumbling shaft, a cut-off indicator in the cab of the locomotive, a cam at the indicator for converting into a single expression factors governing cut-off which produce the maximum results at different speeds, means for actuating the indicator in response to oscillations of the cam and a hydraulic pressure transmitting system extending between the cam and the tumbling shaft for actuating the cam in response to variations in cut-off.

6. In a steam locomotive having a reverse gear, 60 which varies cut-off and includes a tumbling shaft, a cut-off indicator in the cab of the locomotive, a cam at the indicator for converting into a single expression factors governing cut-off which produce the maximum results at different 65 speeds, means for actuating the indicator in response to oscillations of the cam and a hydraulic pressure transmitting system extending between the cam and the tumbling shaft for actuating the cam in response to variations in cut-off.

speeds, a driving hydraulic cylinder adjacent the tumbling shaft, a piston in the cylinder, connections between the tumbling shaft and the driving piston, an operating hydraulic cylinder adjacent the indicator, a piston in the cylinder, connections between the operating piston and the cam, tubing connecting the two cylinders, liquid filling the tubing and cylinders, whereby movement of the driving piston as the tumbling shaft is oscillated to vary cut-off is transmitted to the operating piston to actuate the cam in response to variations in cut-off, and means for actuating the indicator in response to oscillations of the cam.

7. In a steam locomotive having a reverse gear, which varies cut-off and includes a tumbling shaft, a cut-off indicator in the cab of the locomotive, a cam at the indicator for converting into a single expression factors governing cut-off which produce the maximum results at different speeds, means for actuating the indicator in response to oscillations of the cam, a hydraulic pressure transmitting system extending between the cam and the tumbling shaft for actuating the cam in response to variations in cut-off, and

means in the hydraulic pressure transmitting system for adjusting the cam.

8. In a steam locomotive having a reverse gear, which varies cut-off and includes a tumbling shaft, a cut-off indicator in the cab of the locomotive, a cam at the indicator for converting into a single expression factors governing cut-off which produce the maximum results at different speeds, a driving hydraulic cylinder adjacent the tumbling shaft, a piston in the cylinder, connections between the tumbling shaft and the driving piston, an operating hydraulic cylinder adjacent the indicator, a piston in the cylinder, connections between the operating piston and the cam, tubing connecting the two cylinders, liquid filling the tubing and cylinders, whereby movement of the driving piston as the tumbling shaft is oscillated to vary cut-off is transmitted to the operating piston to actuate the cam in response to variations in cut-off, pressure equalizers in the tubing for adjusting the cam, and means for actuating the indicator in response to oscillations of the cam.
